UNITED STATES PATENT OFFICE.

JOHN B. LANG, OF ITHACA, NEW YORK.

CONNECTING-ROD AND PITMAN.

SPECIFICATION forming part of Letters Patent No. 290,332, dated December 18, 1883.

Application filed October 4, 1883. (No model.)

To all whom it may concern:

Be it known that I, JOHN B. LANG, a citizen of the United States, residing at Ithaca, Tompkins county, New York, have invented 5 an Improvement in Connecting-Rods, whereof the following is a specification, reference being had to the accompanying drawings.

My improvement has reference to the tightening of the boxes, especially to those used at 10 the cross-head end of connecting-rods of steam-engines; and it consists in the insertion of a set-screw in cavities in the substance of the rod, longitudinally to its length, that tightens the boxes. Its mode of construction will be 15 apparent as I describe my invention.

Figure 1 is a side of a rod with my device in it. Fig. 2 is a sectional view of the same. Fig. 3 is a section of the rod close to the cross-bar *c*. Figs. 4, 5, and 6 are detached parts, identified 20 by the letters of reference on them.

In the figures, *a* is a part of a connecting-rod, and *b* *b'* the two parts of the boxing for the cross-head journal; and *c* is a bar, made solid with or as a part of the connecting-rod, 25 with a square hole, *c'*, in it, in which is placed the head *h'* of the set-screw *h*, which head is square and bears directly on the boxing. The threaded part of the set-screw extends toward *a'*, the shaft of the rod, and has on it a round 30 movable burr, *e*, against which the round jam-nut *e'* bears, to hold the main burr *e* fast. In the end of the burr *e* is a projection, *f*, from 35 the connecting-rod, which is round, and acts as a journal on which one end of the burr turns, and as a steady-pin, to prevent vibrations or displacements by the quick motions of the connecting-rod. Thus it will be seen that the connecting-rod has the usual boxing, *b* *b'*, put as usual in the end of the rod, 40 but that I make as part of the rod the bar *c*, with a square hole in it, in which is placed the head of the set-screw bolt, while the burrs *e* *e'* are turned; that the said burrs are in a special cavity or mortise made in the end of 45 the connecting-rod, and the displacement of

the end of the burr the farthest from the shaft-journal is avoided by the use of the boss or projection *f*, which enters a bearing-space made in this end of the burr *e*. This makes an advantageous and efficient means for tightening 50 the boxes *b* *b'* about the shaft in the journal-opening *d*.

Several changes in construction may be made—as, for example, the set-screw bar *c* may be made removable and adjustable; but I prefer it to be forged as a solid part of the rod. The burrs *e* *e'* may be octagonal or other shape, with an especial tool to turn them, and so on of other like changes. I have shown round holes *e''* in the burrs, by which they are turned. 60 I bed in the box *b* a steel plate, next to the head of the screw-bolt, as indicated in Fig. 2. The other advantages and parts of my invention are apparent.

What I claim as my invention is—

1. A connecting-rod provided with a set-screw whose head is held in a cross-bar next to the shaft-boxing, and the burr of which, on the thread of the set-screw, bears on the metallic substance of the rod, the set-screw and burr being adjusted in the interior of the rod in the line of its length, as shown and described.

2. The combination of the projection *f* of the connecting-rod with the burr *e* and set-screw *h*, all within the interior of the rod, substantially as described.

3. The transverse cross-bar provided with a four, six, or other sided cavity fitted to receive the head of the set-screw, in combination 80 with the shaft-boxing, set-screw, screw-burrs, and projection on which the burr of the set-screw turns, substantially as shown and described.

JOHN B. LANG.
